(57) **CLAIM**

The ornamental design for an insulated electrical outlet cover, as shown and described.

DESCRIPTION

FIG. 1 is a front perspective view of an insulated electrical outlet cover, showing my new design.

FIG. 2 is a back perspective view thereof;

FIG. 3 is a front elevation view thereof;

FIG. 4 is a back elevation view thereof;

FIG. 5 is a side cross-sectional view thereof, taken along line 5-5 of FIG. 4;

FIG. 6 is a side elevation view thereof;

FIG. 7 is another side elevation view opposite of that shown in FIG. 6;

FIG. 8 is a top plan view thereof; and;

FIG. 9 is a bottom plan view thereof.

The broken lines shown in FIG. 4 represent unclaimed subject matter and form no part of the claimed design.
